(57) **CLAIM**

The ornamental design for a drain stopper, as shown and described.

DESCRIPTION

FIG. 1 is a front, right, top perspective view of a drain stopper, showing my new design;

FIG. 2 is a rear, left, bottom perspective view thereof;

FIG. 3 is a rear, left, bottom perspective view of the drain stopper in another angle;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of detail 10 in FIG. 1;

FIG. 11 is an enlarged view of detail 11 in FIG. 1;

FIG. 12 is an enlarged view of detail 12 in FIG. 1;

FIG. 13 is an enlarged view of detail 13 in FIG. 1;

FIG. 14 is an enlarged view of detail 14 in FIG. 1;

FIG. 15 is an enlarged view of detail 15 in FIG. 2;

FIG. 16 is an enlarged view of detail 16 in FIG. 2;

FIG. 17 is an enlarged view of detail 17 in FIG. 2;

FIG. 18 is an enlarged view of detail 18 in FIG. 2;

FIG. 19 is an enlarged view of detail 19 in FIG. 2;

FIG. 20 is an enlarged view of detail 20 in FIG. 3;

FIG. 21 is an enlarged view of detail 21 in FIG. 3;

FIG. 22 is an enlarged view of detail 22 in FIG. 3;

FIG. 23 is an enlarged view of detail 23 in FIG. 3;

FIG. 24 is an enlarged view of detail 24 in FIG. 3;

FIG. 25 is an enlarged view of detail 25 in FIG. 4;

FIG. 26 is an enlarged view of detail 26 in FIG. 4;

FIG. 27 is an enlarged view of detail 27 in FIG. 4;

FIG. 28 is an enlarged view of detail 28 in FIG. 5;

FIG. 29 is an enlarged view of detail 29 in FIG. 5;

FIG. 30 is an enlarged view of detail 30 in FIG. 6;

FIG. 31 is an enlarged view of detail 31 in FIG. 6;

FIG. 32 is an enlarged view of detail 32 in FIG. 7;

FIG. 33 is an enlarged view of detail 33 in FIG. 7;

FIG. 34 is an enlarged view of detail 34 in FIG. 8;

FIG. 35 is an enlarged view of detail 35 in FIG. 9;

FIG. 36 is a front, right, top perspective exploded view;

FIG. 37 is a rear, left, bottom perspective exploded view;

FIG. 38 is an enlarged view of detail 38 in FIG. 36;

(Continued)

FIG. 39 is an enlarged view of detail 39 in FIG. 36;
FIG. 40 is an enlarged view of detail 40 in FIG. 37;
FIG. 41 is an enlarged view of detail 41 in FIG. 37;
FIG. 42 is an enlarged view of detail 42 in FIG. 37; and,
FIG. 43 is a front, right, top perspective view of the drain
stopper in a state of use.

The dashed broken lines in the figures are for the purposes
of illustrating portions of the drain stopper and form no part
of the claimed design.

The dash-dot-dash broken lines are for notating enlarged
views and form no part of the claimed design.
